(57) **CLAIM**

The ornamental design for a kitchen knife sharpener, as shown and described.

DESCRIPTION

FIG. 1 is a left side view of a kitchen knife sharpener;
FIG. 2 is a front view of the kitchen knife sharpener;
FIG. 3 is a front perspective view of the kitchen knife sharpener;
FIG. 4 is a back perspective view of the kitchen knife sharpener;
FIG. 5 is a back right perspective view of the kitchen knife sharpener;
FIG. 6 is an upper view of the kitchen knife sharpener;
FIG. 7 is a right side view of the kitchen knife sharpener;
and,
FIG. 8 is the bottom view of the kitchen knife sharpener.
The broken lines in the drawings illustrate portions of the kitchen knife sharpener that form no part of the claimed design.

1 Claim, 8 Drawing Sheets
